UNITED STATES PATENT OFFICE.

SPENCER OTIS AND WALTER A. GARDNER, OF CHICAGO, ILLINOIS.

BLOW-OFF PLUG FOR BOILERS.

Application filed February 12, 1921. Serial No. 444,395.

To all whom it may concern:

Be it known that we, SPENCER OTIS and WALTER A. GARDNER, citizens of the United States, residing at Chicago, in the county of Cook and State of Illinois, have invented certain new and useful Improvements in Blow-Off Plugs for Boilers, of which the following is a specification.

This invention relates to a plug to be inserted through the wall of a boiler for the purpose of blowing off the contents of the boiler in cleaning it, and has for its object to provide a blowoff plug which will serve not only to release the fluid contents of the boiler but also to introduce an air blast for stirring up the precipitate of the boiler as a step preliminary to or concurrent with the blowoff.

Accordingly, the invention consists in providing a plug of suitable construction to adapt it to be introduced through the wall of a boiler having controlled passages therethrough, adapted, respectively, for the outflow of water and the injection of air, the air passage being constructed at its inner end with a form that adapts it peculiarly to the development of violent ebullition in the water of the boiler from the air released thereat. The control for the water passage is manually actuated at will, while the control for the air passage is preferably in the form of a check valve, seating with the pressure within the boiler, and unseating to admit air from without when supplied under a sufficient head of pressure.

In the accompanying drawing—

Figure 1 is a view of a portion of a locomotive boiler suggesting one use to which the subject-matter of the present invention may be put.

Figure 2 is a vertical longitudinal section through the plug in a plane which intersects its two passages; and

Figures 3 and 4 are, respectively, an outer end elevation and an inner end elevation of the same.

A represents the fire-box of a boiler B of known construction. C represents a plurality of blowoff plugs embodying the subject-matter of the present invention. As shown in Figure 2, the plug C is intended to be threaded into or otherwise tightly secured at C' to the boiler plate B in position to permit its inner end to assume proper relation to the water to be stirred up and drawn off. As suggested in Figure 1, these plugs may be

arranged in suitable numbers along the mud ring of the boiler, and may also be located over the crown sheet. It is to be understood that the length of the plug, and particularly that portion which extends within the boiler will be varied according to the point beyond the inner face of the boiler plate which it is desired to bring under immediate influence of the plug.

The plug C has a longitudinal passage C² terminating in vertical passage C³, and a flaring discharge nozzle C⁴ through which air is introduced, said passage being guarded against back pressure from the boiler by means of a check valve C⁵ which is guided in the screw plug C⁶ and made readily removable for cleaning the valve. The plug is further provided with a passage C⁷ for water which is controlled by a manually operated valve C⁸ accessible from the outer side of the boiler plate B and which starts with the intake end C⁹ which is preferably closely related to the flaring air nozzle C⁴. The outer ends of the passages C² and C⁷ are adapted to receive pipes, hose fittings, or the like, through which to continue passageways for the elements that are to flow through the passages, for instance, a hose connecting the blowoff passage C⁷ with the blowoff pipe of a boiler washing system, and a flexible connector uniting the passage C² with a suitable source of air under heavy pressure.

An important feature of the preferred embodiment of the invention selected for illustration, is the particular section or form given to that portion of the plug which lies inwardly beyond the threaded portion C', and which is shown in Figure 4. This portion of the plug is relatively narrow so that it offers a minimum resistance to the violent ebullition of the air released through the flaring nozzle C⁴ and permits the volume of air to rise violently through the water and develop the stirring effect desired.

Another important feature of a device of this kind and particularly of the air delivery passage, though not broadly of the present invention, consists in having a prolonged upwardly extending air trap between the discharge end and the air valve, provided in this instance by the vertical leg C³ and inner portion of horizontal leg C² of the air passage in which is trapped, after shutting off the flow, a sufficient body of air to exclude boiler water from the air valve and thereby protect the valve from corrosion.

We claim:

1. A combined air blast and water blow-off plug for steam boilers having controlled passages for air and water therethrough, 5 communicating independently with the interior of the boiler and adapted respectively to deliver air thereto and withdraw water therefrom.
2. A combined air blast and water blow-off plug for steam boilers having controlled 10 passages for air and water therethrough independently communicating with the interior of the boiler; the air passage of said plug terminating in a downwardly presented flaring nozzle.
3. A combined air blast and water blow-off plug for steam boilers having controlled 15 passages for air and water therethrough; the air passage including a downwardly extending portion; and the water passage communicating with the interior of the boiler adjacent the inner end of the air passage.
4. A combined air blast and water blow-off plug for steam boilers having passages 20 for air and water therethrough communicating independently with the interior of the boiler; said water passage having a manually controlled valve; and said air passage having an independently acting valve.
5. In combination with a steam boiler, a 25 combined blowoff and agitating plug fixed in the wall of the boiler and having controlled independent air and water passages therethrough establishing communication

between the interior of the boiler and the 35 exterior thereof and adapted respectively to deliver air into the boiler and release water therefrom.

6. In combination with the mud ring of a 40 steam boiler, a combined air stirring and liquid blowoff plug introduced through the wall of the boiler, and having air and fluid passages therethrough independently communicating with the interior of the boiler adjacent the mud ring and adapted respectively 45 to release air into and withdraw water from the boiler.

7. A combined air stirring and liquid blowoff plug adapted to be introduced into 50 the wall of a boiler, having valved passages for air and blowoff products; the air passage being in the upper part of the plug and communicating with the boiler through a downwardly extending leg, and its valve being located in an upper portion of the 55 passage.

8. A blasting plug for boilers having a horizontally extending air passage with a downwardly extending discharge leg, and a check valve in said passage located in the 60 horizontal part thereof remote from its junction with the downwardly extending discharge leg.

Signed at Chicago, Illinois, this 10th day of February, 1921.

SPENCER OTIS.
WALTER A. GARDNER.
